Primary Examiner — Kelley Donnelly(74) *Attorney, Agent, or Firm* — Marger Johnson & McCollom, PC(57) **CLAIM**

The ornamental design for a flat panel display stand base, as shown and described.

DESCRIPTION

FIG. 1 is a front view of a flat panel display stand base;

FIG. 2 is a back view thereof;

FIG. 3 is a top view thereof;

FIG. 4 is a bottom view thereof;

FIG. 5 is a left view thereof;

FIG. 6 is a right view thereof; and,

FIG. 7 is a perspective view thereof.

The broken lines shown in the drawings are for environmental purposes only and form no part of the claimed design.
